UNITED STATES PATENT OFFICE.

JOHN J. HALLIWELL, OF TUCKAHOE, NEW YORK, ASSIGNOR TO R. HOE & CO., INC., OF NEW YORK, N. Y., A CORPORATION OF NEW YORK.

MULTIPLE-PLATE CLAMPING.

Application filed December 17, 1926. Serial No. 155,434.

This invention relates to certain improvements in plate clamps.

In printing certain classes of products, as, for instance, products having small pages, a large number of plates are used widthwise of the cylinder, as, for instance, it may be desirable to use eight plates across the cylinder. Where such a number of plates are used, the margin spaces between the plates are narrow and it is desirable that the plates may be positioned on the cylinder with the correct margin spaces between each two adjacent plates.

It is a special object of the invention to produce a plate clamp particularly useful for clamping up a large number of plates so that the plate holding clips may be simultaneously operated to release the plates and so that when the plates are clamped the correct margin spaces will be provided between two adjacent plates without the necessity of individual plate adjustment, so that time is saved in plating and unplating a cylinder with these plates.

A further object of the invention is to produce a plate clamp of simple construction and of few parts by which this quick plating of the cylinder may be effected.

With these and other objects not specifically referred to in view, the invention consists in certain novel parts, arrangements and combinations which will be described in connection with the accompanying drawings and the novel features pointed out in the claims hereunto annexed.

In these drawings,—

Figure 1 is an end view of a plate cylinder, partly broken away and partly sectional, showing the improved clamps;

Figure 2 is a plan view of the construction shown in Fig. 1;

Figure 3 is a horizontal broken sectional view showing the clamps as clamping four plates wide on one end of the cylinder, the clamps being shown as open;

Figure 4 is a similar view showing the clamps in locked position, and

Figure 5 is a plan view of part of the construction shown in Fig. 4, certain of the plates having been removed.

Referring now to the drawings, the invention has been illustrated as used for clamping a plurality of relatively narrow plates on the cylinder, four such plates be-

ing shown on one half of the cylinder. It will be understood, however, that the invention is not to be limited to this number of plates, but may be used with varying numbers, as conditions may require.

In the construction shown, there is provided a plate cylinder 1 capacitated to carry four plates wide on each end of the cylinder, only one end of the cylinder being shown, it being understood that the construction is duplicated on the other end. The plates shown are marked 3, 4, 5, 6 and 7. This cylinder is provided with a fixed margin bar 2 against which the inside of the two inside plates 6, 7 abut.

Plate clamps or clips are employed for locking up the plates 3, 4, 5 and 6, and, in accordance with the invention, means are provided whereby a plurality of these clamps may be simultaneously operated to clamp and release the plates, and, in the best constructions, these means are such as to move the clamps in either direction a predetermined distance so that when the plates are in clamped position the margin spaces between the plates will be of the same desired width. While these means may vary somewhat, in the particular construction shown there are provided four clamps 8, 9, 10 and 11, three of these clamps, as 9, 10 and 11 being simultaneously movable to clamp and release the plates, and the fourth clamp, as 26, being independently operated to clamp and release the outside plate.

In the best constructions, furthermore, means are provided whereby the clamping members for clamping the outside edges of the three inside plates 4, 5 and 6 may be independently adjusted in the event that the simultaneous operating means do not effect quite the desired clamping effect.

In the clamping mechanism selected to illustrate the invention, the clamps 9, 10 and 11 clamp the inside edges of the three inside plates, and these clamps are provided with independent operating clamps or clips 12, 13 and 14, which are provided with bevelled portions for engaging the bevelled outside edges of the inside plates. These clamps are mounted and operated so that the clamps 9, 10 and 11 will be simultaneously moved either to the right or left to simultaneously clamp and release the plate, and preferably this movement will be one which may be pre-

determined so that the clamps will be returned to the same position and give the proper margin space.

While this may be effected in various ways, in the particular construction illustrated, the cylinder is circumferentially grooved, as indicated at 15' in Fig. 2, in which grooves are fitted rings 16' which are formed with rectangular recesses, indicated at 17' in Fig. 1, and the clamp blocks 8, 9, 10 and 11, before referred to, are mounted in these recesses. The cylinder is also channelled longitudinally, as indicated at 15, and through this channel extends a screw actuator rod 19. The blocks 9, 10 and 11 are operated by the screw rod 19, and this rod is formed with a collar 19', see Fig. 4, which engages a thrust plate 20, the end of which is squared, as indicated at 20', to fit a wrench. Blocks 17 are secured in the channel 15 by means of screws 16, these blocks being grooved on the under side, as indicated in Fig. 1, to clear the screw rod 19, and serve to close the openings required for the insertion of the clamps 8, 9, 10 and 11 in the cylinder.

This screw actuator rod is provided at intervals along its length with threaded portions which pass through and engage threaded apertures of the clamp blocks 9, 10 and 11, but has a free sliding movement in the block 8. The threads of the screw actuator rod are different for each of the clamps; thus the part of the rod which engages the clamp block 11 has a single thread, indicated at 21, that which engages the clamp 10 has a double thread, indicated at 22, and that which engages the block 9 has a triple thread, indicated at 23. With this construction, it will be seen that the clamp block 10 will move twice the distance of the block 11, and the block 9 will move three times the distance of block 11, that is, each block will move the required distance to unclamp the plates engaged thereby, so that all the plates will be simultaneously freed. If desired, the screw rod, instead of being made in one piece, may be made in sections joined by a tongue and groove 24 pinned together by pins 25.

It will thus be seen that by loosening the clamp 26 all the rest of the clamps can be simultaneously moved to release the plates by the operation of the screw actuator rod 19. In clamps embodying the invention in its best form, means will be provided for providing an individual adjustment of the plate engaging portions of the clamps relatively to the clamp blocks which are simultaneously moved by the screw actuator rod. While this may be done in various ways, as shown, the clamps 12, 13 and 14 and the clamp 26 are mounted to have a sliding movement relatively to the clamp blocks 8, 9, 10 and 11, before referred to. As shown,

see Fig. 1, these latter clamp blocks are provided with a rectangular recess, indicated at 27, in which these clamp blocks may have a sliding movement, and the blocks are operated by operating screws 28 having gears 29, these screws having suitable bearings in the blocks. With this construction, the small clamps may have a movement relatively to the clamp blocks for individual adjustment of the clamps. If desired, means may be provided for locking the gears 29 against movement, which means, of course, may be varied, but, as shown, comprise a resilient locking strip 30 suitably secured to the main clamp blocks by screws 31, or in any other suitable way. The smaller clamps 12, 13, 14 have a movement relatively to the large clamp blocks, but move with the clamp blocks 9, 10, 11 by reason of the screws engaging plates 32, secured to the ends of the blocks.

While the invention has been shown and described in its preferred form, it will be understood that various changes may be made in the specific construction and arrangement of the parts without departing from the invention as defined in the appended claims.

What I claim is:

1. In a plate clamp, the combination of a plate support, a plurality of plates on the support widthwise thereof, a movable clamp for each plate, and means for simultaneously moving a plurality of the clamps different distances for simultaneously locking and releasing a plurality of the plates.

2. In a plate clamp, the combination of a plate support, a plurality of plates on the support widthwise thereof, means for simultaneously moving a plurality of the clamps different distances for simultaneously locking and releasing a plurality of the plates, and means for effecting an independent adjustment of each of the clamps.

3. In a plate clamp, the combination of a plate support, a plurality of plates on the support widthwise thereof, a movable clamp for each plate, and a clamping rod engaging a plurality of the clamps for moving them different distances simultaneously for simultaneously locking and releasing a plurality of the plates.

4. In a plate clamp, the combination of a plate support, a plurality of plates on the support widthwise thereof, a plurality of clamp blocks having plate engaging clips, means common to the blocks for simultaneously moving a plurality of them, and clamps moving with the blocks but independently movable relatively thereto for individual adjustment.

5. In a plate clamp, the combination of a plate support, a plurality of plates on the support widthwise thereof, a plurality of clamp blocks having plate engaging clips, a

screw rod engaging the clamps and having threads of different pitch for simultaneously moving a plurality of the clamp blocks, and clamps moving with the blocks but independently movable relatively thereto for individual adjustment.

6. In a plate clamp, the combination of a plate support, a plurality of plates on the support widthwise thereof, a plurality of 10 clamp blocks having plate engaging clips, a screw rod engaging the clamps and having threads of different pitch for simultaneously moving a plurality of the clamp blocks, clamps moving with the blocks but independently 15 movable relatively thereto for individual adjustment, and means for locking the latter clamps against movement relatively to the blocks.

7. In a plate clamp, the combination of a 20 plate support, a plurality of plates on the

support widthwise thereof, a plurality of clamp blocks having plate engaging clips, means common to the blocks for simultaneously moving a plurality of them, clamps moving with the blocks but independently 25 movable relatively thereto for individual adjustment, and means for locking the latter clamps to the blocks.

8. In a plate clamp, the combination of a plate cylinder, circumferential grooves in the 30 cylinder, rings located in the grooves provided with recesses, clamps in the recesses and arranged lengthwise of the cylinder, and a screw actuator rod engaging a plurality of the clamps for simultaneously operating 35 them.

In testimony whereof, I have hereunto set my hand.

JOHN J. HALLIWELL.
